United States Patent Office

Des. 206,111
Patented Oct. 25, 1966

206,111

SHOE TREE

Ivor J. Allsop, Bellingham, Wash., assignor to Allsop
Automatic Company, Bellingham, Wash.

Filed Apr. 26, 1965, Ser. No. 84,971

Term of patent 14 years

(Cl. D87—5)

FIG. 1 is a top plan view of a boot or shoe tree, showing my new design;

FIG. 2 is a front elevational view thereof;

FIG. 3 is a side elevational view thereof; and

FIG. 4 is a rear elevational view thereof.

I claim:

The ornamental design for a shoe tree as shown.
